(57) **CLAIM**

What is claimed is a balloon with shot carrier, as shown and described.

DESCRIPTION

FIG. 1 is a left front perspective view of a balloon with shot carrier showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a right front perspective view thereof with the lid in an opened condition.

The broken line showing of the balloon and string in FIG. 1 is included for the purpose of illustrating environment and forms no part of the claimed design.
